SIGNALING SYSTEM.

1,105,350.

Specification of Letters Patent.

Patented July 28, 1914.

Application filed July 15, 1912. Serial No. 709,429.

To all whom it may concern:

Be it known that I, MORTON L. JOHNSON, citizen of the United States, residing at Chicago, in the county of Cook and State of Illinois, have invented a certain new and useful Improvement in Signaling Systems, of which the following is a full, clear, concise, and exact description, reference being had to the accompanying drawings, forming a part of this specification.

My invention relates to signaling systems and has for its object the provision of such a system in which a plurality of signal sending lines may be separably associated with 15 a signal receiving instrument which is interchangeably associated with the sending lines by means of suitable selector switching mechanism, there being preferably provided a plurality of signal receivers less in number than the sending lines, the selector mechanism serving to associate sending lines with idle signal receivers to the exclusion of signal receivers previously associated with other sending lines.

25 My invention is of particular service in connection with telephone exchange systems and by means of the invention I am enabled to receive and, if desired, to record the numbers of calling lines by signal receivers that are less in number than the lines and which are selectively associated with the lines in the general manner which has been described. These signal receivers may, if desired, be individual to the operators' 30 positions and the circuits for effecting their operation may, if desired, be accompanied by conductors constituting selected extensions of calling lines with which the operators' telephones may be connected in order that the operators may ascertain the numbers of the called lines, the signal receivers then serving to indicate to the operators the numbers of the calling lines. When the operators have been informed automatically 40 of the numbers of the calling lines by means of said signal receivers and have been informed by the calling subscribers of the numbers of the desired lines, the operators may proceed to connect the calling and 45 called lines by usual or preferred equipment.

50 I will explain my invention more fully by reference to the accompanying drawings in which—

Figures 1 and 2, taken collectively with 55 the conductors at the tops of the sheets in alinement, illustrate a telephone exchange system having the signaling system of my invention.

I have shown but one telephone line extending to station No. 1357, though it will be understood that there are many telephone lines of the kind illustrated extending to this telephone station and the description of one line equipment will therefore suffice for a description of the other line equipments which I have not illustrated. At the telephone station illustrated I have shown a telephone switch hook having a normal contact which is engaged therewith through the influence of the telephone receiver 2 when upon the switch hook, whereby a signal bell bridge including a signal bell 3 and a condenser 4 is connected between the sides of the line. The telephone switch hook 1 has an alternate contact which is engaged thereby when the receiver 2 is removed, whereby a telephone bridge is established between the sides of the line and which bridge includes a telephone receiver 2 and telephone transmitter 5. The line sides terminate at the exchange in the armature switches of a cutoff relay 6 having alternate contacts that are engaged by the armature switches when calling lines are extended whereby the multiple jacks 7 are connected with lines, whether calling or called so that the operator may connect the calling and called lines by means of any preferred equipment such as the cord circuit 90 link connector equipment illustrated at 8. I will not describe the link connectors 8 as the illustration furnished will be sufficient to enable the same readily to be understood by those skilled in the art. I have illustrated another telephone line extending from the station A to the exchange and there provided with multiple jacks 9, it being understood that there may be a number of such lines, the line extending to station A not being equipped with the apparatus of the invention, though of course the invention is not to be limited to lines of the mixed character extending to station 1357 and station A. The line extending to station A has been 105 illustrated as an ordinary manual telephone line in order to simplify the illustration of the system employing my invention.

It may be assumed that station 1357 is a calling station and that station A is a called station. When the calling party at station 1357 removes his telephone receiver 2 from its switch hook circuit is established by way of the armature switches of the cutoff relay 6 and their normal contacts which may be traced from the grounded battery 10, the upper coil of relay 11, the upper armature switch of relay 6, and its normal contact, one side of the calling line, the telephone bridge at the calling station, the other side of the calling line, the lower armature switch of relay 6 and the normal contact of this latter armature switch, to the grounded lower coil of the relay 11. The relay 11 upon being thus energized attracts its grounded armature switch to establish a circuit which may be traced from this switch and its alternate contact, the sluggishly operating interrupter relay 12, the motor magnet 13, the side switch wiper 14 in its first position, to the grounded battery 10. The motor magnet 13 thus sets the wipers 15, 16, 17 and 18 into operation until the wiper 15 encounters an ungrounded contact whereupon the private relay 19 (whose circuit was previously closed upon the initial energization of the motor magnet 13) is deenergized, this private relay thereupon moving the side switch wipers 14 and 20 to their second positions, the side switch wiper 14 in its second position opening the circuit of the magnet 13 whereby the wipers 15, 16, 17 and 18 are arrested. When the side switch wiper 20 is in its second position it engages a grounded contact whereby the wiper 15 of the actuated selector switch is grounded and the contact engaged by the wiper 15 is grounded together with other contacts in multiple with this contact that are distributed among other selector switches which are operable by other calling lines whereby such other selector switches will not stop with their wipers 15 upon contacts thus grounded so that calling subscribers will not cause the wipers of selector switches which they operate to rest upon contacts that are in multiple with contacts of other selector switches whose wipers are in electrical connection therewith. It will be understood that the waiting contacts of the wipers 15, 16, 17 and 18 of the different switches are respectively multiplied. I have shown the selector switch associated with line 1357 as being individual to that line though the invention is not to be limited to this individuality. When the wiper 15 has engaged an ungrounded contact the companion wipers are in connection with conductors which lead to signal receiving equipment that is free to be associated with the calling line and with telephone conductors that lead to the operator's position having signal receiving equipment.

I have shown two well known ticker re-

corders which may be employed in practising the invention, each recorder being illustrated as belonging to an operator's position within range of the operators at these positions. Each recording signal instrument illustrated includes a polarized magnet 21 whose armature oscillates the well known ratchet wheel actuating device 22, the ratchet wheel 23 which is actuated being fixed upon a shaft 24 that carries a printing wheel 25 provided with printing characters, the said shaft also carrying a weighted pulley 26 for turning the shaft when it is permitted to turn by the operation of the magnet 21. The equipment also includes a printing magnet 27 whose armature presses a paper tape 28 against the printing wheel 25 when printing is to be effected. The periphery of the printing wheel 25 is inked by an inking roller 29. The paper tape is fed in any suitable way familiar to those skilled in the art.

Direct currents of opposite polarity are applied alternately to the winding of the polarized magnets 21 whereby the shafts 24 are continuously kept in rotary stepping movement, the shafts 24 being turned step by step in order that the printing characters upon the faces of the printing wheels 25 may be properly presented to the tape. I have shown a source of grounded direct current 30 for impressing current of positive polarity upon the magnets 21 and a source of grounded direct current 31 for impressing current of negative polarity upon the magnets 21. The positive and negative terminals, respectively, of the sources of current 30 and 31 are connected by brushes with disks 32, 33 that are fixedly mounted upon an insulated shaft 34 driven by a motor 35. These disks are provided with metallic continuations 36 which are flush with sections of insulating material 37. Brushes 38, 39 are successively engaged by the projections 36, the engagement between one brush and each finger 36 of one disk being followed 30° later by engagement between the other brush and the finger 36 of the other disk. The brushes 38 and 39 constitute multiplied terminals of each polarized magnet 21, the other terminal of each of these magnets 21 being grounded. Two of the fingers or projections 36 upon each disk 32, 33 are spaced 120° apart and the remaining fingers or projections are spaced 60° apart, there thus being five such fingers to each disk. Each disk thus causes the energization of each magnet 21 five times in each disk revolution, each of the five energizations occasioned by one disk being followed 30° later by the energization of the magnets 21 effected by the other disk. As these disks direct positive and negative current respectively to the polarized magnets 21 the armatures of these magnets have five complete oscillations for each revolution of the shaft 34. The shaft 24

thus has eight periods of rest that prevail throughout substantially 320° of rotation of the shaft 34 and two periods of rest that prevail substantially throughout 60° of rotation of the shaft 34, the shaft 24 thus having ten periods of rest during each revolution of the shaft 34. The equipment having the elements 21 to 39, inclusive, is well known by those skilled in the art. Each telephone line has individually related thereto a ratchet wheel 40 which is adapted to be stepped around by a motor magnet 41 that operates a pawl 42 in engagement with the ratchet. Each line has a switch 43 individual thereto and employed for connecting the battery 10 with the motor magnet, this switch 43 being closed by means of a relay 44 (one for each line) when it is energized upon the location of the side switch wiper 14 of the actuated selector switch in its second position by means of a circuit which is so clear as to need no description. The shaft 34 carries a disk 45 that has electrical connection with a brush 46 but once during each revolution of the shaft 34. Circuit having been previously partially established for the motor magnet 41 at 43, circuit for this magnet is completed once on each revolution of the shaft 34 so that the wheel 40 is stepped around. The wheel 40 has fixed thereupon wipers 47, 48, the wiper 48 engaging a segmental contact while the wiper 46 is attracted for successive engagement with contact buttons. Wheel 40 and the wipers 47 and 48 are adapted to be stepped around as long as the wiper 48 engages its segmental contact, the circuit for the motor magnet 41 being opened to prevent further operation of the wheel 40 when the wiper 48 leaves its segmental contact, whereafter the wheel 40 is restored to normal by mechanism which will be described. It should be stated that circuit is closed through the magnet 41 (owing to the relationship of the disk 45 with respect to the disks 32 and 33) substantially 30° before disk 32 closes circuit and 60° before disk 33 closes circuit, the magnets 41 being energized during the periods that the brushes 38 and 39 are between the most widely separated fingers 36 of the disks 32 and 33, whereby ample opportunity is afforded for stepping the wiper 47 from one contact button to another.

The shaft 34 also carries ten disks 49, 50, 51, 52, 53, 54, 55, 56, 57 and 58 that are respectively engaged by brushes 49¹, 50¹, 51¹, 52¹, 53¹, 54¹, 55¹, 56¹, 57¹ and 58¹ once upon each revolution of the shaft 34. The disks 49 to 58 inclusive are so related that their brushes are engaged in succession at intervals of 30° of the revolution of the shaft 34. The first disk 49 engages its brush 49¹ after the disk 45 engages its brush 46, by which arrangement the brushes 49¹ to 58¹ are electrically connected with one terminal of a

grounded battery 59 during the time that the printing wheels 25 are at rest. The peripheries of the printing wheels, for the purpose of my present invention, are provided with printing characters in the form of digits. The brush 49¹ is connected with the battery 59 when the printing wheels 25 are presenting digits 1 to the tapes 28; the brush 50¹ is connected with the battery 59 when the printing wheels 25 are presenting digits 2 to the tapes 28; the brush 51¹ is connected with the battery 59 when the printing wheels 25 are presenting digits 3 to the tapes 28, and so on, brushes 52¹, 53¹, 54¹, 55¹, 56¹, 57¹ and 58¹ being, respectively connected with the battery 59 when the printing wheels are presenting the digits 4, 5, 6, 7, 8, 9 and 0 to the tapes 28. Each telephone line is provided with as many waiting contacts for its wiper 47 as there are digits in the number assigned to such telephone line. These waiting contacts are connected with those of the brushes 49¹ to 58¹, inclusive, that are connected with the battery 59 when the digits of the printing wheels 25 corresponding to calling lines are presented to the tape 28 belonging to the selected printing magnet 27, the magnets 27 constituting the portions of the signal receiving equipments that are selectively associated with the lines so that the tapes belonging thereto may receive record of the different calling lines that have selected the printing magnets pertaining thereto. Thus in the case of telephone station 1357 the lowermost button is connected with brush 49¹, the next button above is connected with brush 51¹, the next button above the latter button is connected with the brush 53¹ and the topmost button is connected with the brush 55¹. The wiper 47 individual to each line is included in circuit connection with the selected printing magnet 27 by means of the wiper 18, one terminal of each printing magnet 27 being grounded while the other terminal of each printing magnet is multiplied in the different selector switches, each selector switch having a waiting contact for its wiper 18 that belongs to but one printing magnet.

By the equipment which has been described the number of the calling line is printed upon the tape 28 of the selected printing magnet 27, this operation being preferably performed within view of the operator who thereupon may depress her listening key 60 to bring her telephone set 61 into circuit with the talking wipers 16 and 17 and thereby into circuit with the calling line to ascertain from the calling subscriber the number of the desired line whereafter the operator may, by any suitable or preferred means connect the calling and called lines. I have shown well known cord connecting equipment 8 and well 180

known multiple jack structure 7 and 9 whereby calling and called lines may be connected and as this equipment is well understood by those skilled in the art further description thereof will not be necessary excepting to state that the ratchet wheel 40 is restored to normal when a plug is inserted in the jack of a calling line. When the jack of a calling line receives a plug, circuit 10 is established through the cutoff relay 6 in a well known manner. As a consequence of which the circuit of relay 11 is opened so that the armature switch of relay 11 engages its normal contact to establish circuit 15 through the release magnet 62 and the previously closed contacts of the off normal switch 63. The magnet 62 causes the side switch wipers 14 and 20 to be restored to their initial positions and the wipers 15, 16, 20 17 and 18 are also restored to normal positions. When the side switch wiper 14 is restored to normal position circuit for the magnet 44 is opened whereby the upper armature switch of this magnet establishes 25 a circuit that may be traced from the grounded battery 10 through the upper armature switch of magnet 44, the winding of release magnet 64, the contacts 65 that were closed upon the initial movement of the ratchet wheel 40, to ground. The release magnet 64 thereupon withdraws the dog 66 from engagement with the wheel 40 whereupon the spring 67 will restore the wheel 40 to normal, the wheel carrying the 30 wipers 47, 48 to normal.

Those familiar with the art are acquainted with the system disclosed in British Patent 1298 of 1910 and are also familiar with the mechanical construction of the switches described in Van Deventer's "*Telephonology*," 40 page 530, and it will therefore be unnecessary to describe in detail the selector switches which I have employed for selecting the responsive devices 27 that are free for selection. In my applications Serial Nos. 45 709,423 and 709,424 I have also disclosed and claimed equipment for automatically apprising the operators of the numbers of telephone lines.

While I have herein shown and particularly described the preferred embodiment of my invention, I do not wish to be limited to the precise details of construction and circuit arrangement illustrated as changes may 55 readily be made without departing from the spirit of my invention, but

Having thus described my invention I claim as new and desire to secure by Letters Patent the following:

60 1. A signaling system including a plurality of signaling lines; visual signal receivers; selector switches for selecting signal receivers that are free for selection and associating the same with signaling lines; and 65 means individual to the lines and which dif-

fer from each other for causing said signal receivers to give characteristic signals peculiar to the lines.

2. A signaling system including a plurality of signaling lines; recording signal receivers; selector switches for selecting signal receivers that are free for selection and associating the same with signaling lines; and means individual to the lines and which differ from each other for causing said signal receivers to give characteristic signals peculiar to the lines.

3. A signaling system including a plurality of signaling lines; signal receivers; selector switches for selecting signal receivers that are free for selection and associating the same with signaling lines; means individual to the lines and which differ from each other for causing said signal receivers to give characteristic signals peculiar to the lines; a plurality of circuits for effecting successive operations of each signal receiver; and means set into operation by each signaling line and associated with the selected signal receivers that are free for selection and for establishing the signal receiver controlling circuits of a signaling line in succession through the selected signal receiver.

4. A signaling system including a plurality of signaling lines; recording signal receivers; selector switches for selecting signal receivers; that are free for selection and associating the same with signaling lines; means individual to the lines and which differ from each other for causing said signal receivers to give characteristic signals peculiar to the lines; a plurality of circuits for effecting successive operations of each signal receiver; and means set into operation by each signaling line and associated with the selected signal receiver by the operated selector switch for establishing the signal receiver controlling circuits of a signaling line in succession through the selected signal receiver.

5. A signaling system including a plurality of signaling lines; visual signal receivers; selector switches for selecting signal receivers that are free for selection and associating the same with signaling lines; means individual to the lines and which differ from each other for causing said signal receivers to give characteristic signals peculiar to the lines; a plurality of circuits for effecting successive operations of each signal receiver; and means set into operation by each signaling line and associated with the selected signal receiver by the operated selector switch for establishing the signal receiver controlling circuits of a signaling line in succession through the selected signal receivers.

6. A telephone system including a plurality of telephone lines extending to exchange operators' positions; visual signal receivers at said operators' positions; selector switches,

for selecting signal receivers that are free for selection and associating the same with calling lines; and means individual to the lines and which differ from each other for causing said signal receivers to give characteristic signals peculiar to the calling lines.

7. A telephone system including a plurality of telephone lines extending to exchange operators' positions; recording signal receivers at said operators' positions; selector switches for selecting signal receivers that are free for selection and associating the same with calling telephone lines; and means individual to the lines and which differ from each other for causing said signal receivers to give characteristic signals peculiar to the calling lines.

8. A telephone system including a plurality of telephone lines extending to exchange operators' positions; signal receivers at said operators' positions; selector switches for selecting signal receivers that are free for selection and associating the same with calling telephone lines; means individual to the lines and which differ from each other for causing said signal receivers to give characteristic signals peculiar to the lines; a plurality of circuits for effecting successive operations of each signal receiver; and means set into operation by each calling telephone line and associated with the selected signal receiver by the operated selector switch for establishing the signal receiver controlling circuits of a calling telephone line in succession through the selected signal receiver.

9. A telephone system including a plurality of telephone lines extending to exchange operators' positions; recording signal receivers at said operators' positions; selector switches for selecting signal receivers that

are free for selection and associating the same with calling telephone lines; means individual to the lines and which differ from each other for causing said signal receivers to give characteristic signals peculiar to the lines; a plurality of circuits for effecting successive operations of each signal receiver; and means set into operation by each calling telephone line and associated with the selected signal receiver by the operated selector switch for establishing the signal receiver controlling circuits of a calling telephone line in succession through the selected signal receiver.

10. A telephone system including a plurality of telephone lines extending to exchange operators' positions; visual signal receivers at said operators' positions; selector switches for selecting signal receivers that are free for selection and associating the same with calling telephone lines; means individual to the lines and which differ from each other for causing said signal receivers to give characteristic signals peculiar to the lines; a plurality of circuits for effecting successive operations of each signal receiver; and means set into operation by each calling telephone line and associated with the selected signal receiver by the operated selector switch for establishing the signal receiver controlling circuits of a calling telephone line in succession through the selected signal receiver.

In witness whereof, I hereunto subscribe my name this third day of July A. D., 1912.

MORTON L. JOHNSON.
